UNITED STATES PATENT OFFICE.

EARL V. GODFREY, OF GIRARD TOWNSHIP, ERIE COUNTY, PENNSYLVANIA, ASSIGNOR TO LOVELL MANUFACTURING COMPANY, OF ERIE, PENNSYLVANIA, A CORPORATION OF PENNSYLVANIA.

DESIGN FOR A CLOTHES-WRINGER FRAME.

Application filed June 16, 1928. Serial No. 27,158. Term of patent 14 years.

To all whom it may concern:

Be it known that I, EARL V. GODFREY, a citizen of the United States, residing in Girard Township, in the county of Erie and State of Pennsylvania, have invented a new, original, and ornamental Design for a Clothes-Wringer Frame, of which the following is a specification, reference being had to

the accompanying drawing, forming a part thereof.

The figure is a perspective view of a clothes wringer frame showing my design.

I claim:

The ornamental design for a clothes wringer frame, as shown.

EARL V. GODFREY.
